UNITED STATES PATENT OFFICE.

HARRY BRANDENBERGER, OF BALTIMORE, MARYLAND.

SHOW-WINDOW AND SHOW-CASE.

No. 823,203.

Specification of Letters Patent.

Patented June 12, 1906.

Application filed October 20, 1905. Serial No. 293,617.

To all whom it may concern:

Be it known that I, HARRY BRANDENBERGER, a citizen of the United States, residing at the city of Baltimore, State of Maryland, have invented new and useful Improvements in Show-Windows and Show-Cases, of which the following is a specification.

This invention relates to show-windows, show-cases, and the like, and particularly refers to metal corner-posts or division-bars for setting and connecting polished plate-glass, as well as other kinds of glass.

The primary object of the invention is to provide a novel construction of metal corner-post or division-bar which will reliably and positively connect the meeting end edges of plates of glass whether they be disposed at varying angles or in longitudinal alinement without resorting to the formation of openings through the glass adjacent to the connected edges.

A further object of the invention is to provide a simple form of corner-post or division-bar which will present a neat and ornamental appearance when applied.

In the drawings, Figure 1 is a horizontal section through a corner-post and portions of glass plates embodying the features of the invention. Fig. 2 is a detail side elevation 30 of the corner-post shown by Fig. 1 broken through the center to shorten the same. Fig. 3 is a view similar to Fig. 1, showing a slight modification. Fig. 4 is a view similar to Fig. 2, showing a slight modification. Fig. 5 is a view similar to Fig. 4, showing a still further modification. Figs. 6, 7, and 8 are views similar to Figs. 1, 3, and 4, embodying other modifications of the invention.

Similar numerals of reference are employed to indicate corresponding parts throughout the several views.

In all the forms of the corner-post or division-bar, three essential elements are embodied, consisting of a facing, an angular bracing-post, and a securing or fastening screw device, the number of the latter used being dependent upon the height of the post or the division-bar.

In Fig. 1 the facing 1 has a polygonal contour with a flat front 2 and angular wings 3, the wings projecting rearwardly and outwardly from the intermediate flat front. In Fig. 3 the facing 4 is of arcuate contour. Fig. 4 illustrates a facing 5 having a reduced central front 6 and elongated or extended angular

wings 7. Fig. 5 shows a facing 8, which is straight to adapt the structure for use as a division-bar. Fig. 6 also illustrates the organization of essential elements arranged to serve as a division-bar, and the facing 9 in this instance is polygonal and somewhat similar to the construction of facing shown by Fig. 1. Fig. 7 shows a facing 10 having an intermediate or central reduced front 11 and wings 12 of slightly less angle than the wings 7. 65 (Shown by Fig. 4.) The facing 13 (illustrated by Fig. 8) has a central arcuate portion 14 and angular wings 15 arranged at about the same angle as the wings 7. (Illustrated by Fig. 4.) Each of the facings just described is assembled in co-operative relation with a bracing-post 16, corresponding in height to the glass plates held by the improved structure, the post 16 being square in cross-section and arranged in each instance with one diagonal 75 thereof in alinement with the center of the facing and back a sufficient distance from the latter to leave ample space or compensate for the thickness of the glass plates 17. The post 16 is disposed in parallel relation to the 80 facing in each instance and has upper and lower terminal lugs 18, which are suitably tapped to receive screws 19 for fastening the post to the top and bottom of a show-window or the framing of a show-case. The 85 wings or inner portions of the several facings which bear against the glass plates are provided with strips 20 of felt or other soft material, and the sides of the bar 16, against which the said glass plates have bearing, are 90 similarly provided with strips 21 of felt or other material, as clearly shown by Figs. 1, 3, 4, 6, 7, and 8. The facing 8 (illustrated by Fig. 5) has a continuous strip 22 of felt on its inner side to bear against contiguous edge 95 17.

In the form of the device shown by Figs. 5, 6, and 7 angular springs 23 are interposed between the plates 17 and the adjacent faces of the post or bar 16. Between the outer 100 sides of the springs 23 and the plates 17 felt or other buffering strips 24 are interposed. The springs 23, as shown by Figs. 5 and 6, have a right-angular cross-sectional contour to hold the plates 17 in longitudinal alinement and adapt the organization of elements embodying the invention to be used as a division-bar, the felt or other strips 21 in Fig. 6 being interposed directly between the ends of the wings of the facing and the plates 17. By 105 110

modifying the angle of the cross-sectional contour of the springs, as at 25, Fig. 7, the plates 17 may be held at an angle to each other with the same advantages in corner-
5 post construction as shown by Figs. 1, 3, 4, and 8.

In the forms of the device illustrated by Figs. 1, 3, 4, 5, 6, and 7 fastening-screws 26 are inserted at regular intervals through the 10 centers of the facings in the posts, the heads of the screws being countersunk in the facings and the screw-threaded terminals thereof embedded in the posts.

In the form of the device shown by Fig. 8 15 the screws are brazed, as at 27, to the inner side of the facing, and the screw-threaded extremities 28 are inserted through threaded openings in the post or bar 16 to receive nuts 29, which are turned up against the inner 20 portion of the said post. The glass plates 17 where the screw-fastening devices pass therethrough are nicked, as at 30, to permit the said screws to pass therebetween and provide a tight joint or contact between the adjacent 25 edges of the said plates. It is proposed to form each of the facings shown and described of metal of any kind suitable to the purpose—such as brass, copper, nickel, steel, iron, aluminum, &c. In addition to the buffering function 30 of the felt or other soft strips interposed between the facings and the plates and the latter and the springs and posts, said strips serve to provide water and dust proof joints. In the operation of chipping the glass plates 35 for the passage of the screw-fastening devices nicks of such depth only will be formed as to just permit the screw devices to pass between the plates 17, and care of course will be taken in this nick formation 40 to avoid fracturing the glass plates. Another advantage of this improved post and division-bar is that obstruction to light or view within the show-window is reduced to a minimum consistent with retaining the 45 greatest strength possible for safely supporting large glass plates. Another advantage derived from the improved construction is that where breakage of the plates occur they may be replaced by other plates from the 50 outside of the window or the case without disturbing the interior of a trimmed window. Further advantages present are that the joints do not have to be beveled, the use of cement at the joints is entirely unnecessary, 55 and as all the parts are formed of metal there is no liability of injury due to rotting or breaking, as in wood structures. Furthermore, the cost of manufacture of the several

parts is materially reduced in view of the 60 simplicity of the same.

Having thus described the invention, what is claimed as new is—

1. In a device of the class set forth, the combination of glass plates having their edges arranged in close relation, an inner angular vertically-extending post against which the inner sides of the edges of the plates are braced, the post having securing devices at the upper and lower ends thereof, a facing applied over the outer portions of the contiguous edges of the plates, and fastening means extending inwardly from the facing and held in the post, said fastening means passing between the contiguous edges of the plates. 70

2. In a device of the class set forth, the combination of glass plates having edges thereof in contact with each other, an inner post against which the inner portions of the plates are braced, a facing over the outer portions 80 of the plates having angular terminals exerting a pressure on the latter, the post being provided at its upper and lower terminals with securing means serving to hold said post in positive position, and fastening means extending inwardly from the center of the faces between the contiguous edges of the plates and engaging the post. 85

3. In a device of the class set forth, the combination of glass plates with contiguous 90 edges, a post against which the inner portions of the plates are braced, said post having angular securing-lugs at the upper and lower ends thereof, a facing extending over the outer portion of the edges of the plate, and 95 fastening means extending inwardly from the facing through the contiguous plate edges and into the post.

4. In a device of the class set forth, the combination of glass plates with contiguously-arranged edges, a facing over the outer portion of the plate edges, an angular post located at a distance inwardly from the facing and between which and the latter the edges of the plate are inserted, spring devices interposed between the plate edges and post, and fastening means extending inwardly from the facing between the plate edges and projecting into the post. 100

In testimony whereof I affix my signature 110 in presence of two witnesses.

HARRY BRANDENBERGER.
